ELECTRIC SWITCH

Mannes N. Glickman, Nutley, N. J.

Original application August 31, 1948, Serial No. 47,050, now Patent No. 2,597,080, dated May 20, 1952. Divided and this application December 15, 1951, Serial No. 261,808

7 Claims. (Cl. 200—152)

1

This invention relates to electric switches of the liquid contact, mercury type. This application is a division of application Ser. No. 47,050, filed August 31, 1948, now Patent No. 2,597,080, May 20, 1952.

An object of this invention is to provide an electric switch which includes a movable circuit closing element and a switch housing for mounting such element.

Another object of this invention is to provide a switch construction including a housing and a switch body mounted for movement in the housing and comprising exteriorly projecting terminals, the housing having contact strips which are slidably engaged by the terminals as the switch body is moved between its "on" and "off" positions.

A further object of this invention is to provide a switch construction including a housing and a switch body of the mercury contact type, the switch body being rotatable about a transverse axis and including eccentrically disposed terminals which are adapted to move from positions below and above the level of the mercury as the body is rotated, the housing being provided with arcuate contact strips which are slidably engaged by exterior portions of the switch body as the same is rotated.

Yet a further object of this invention is to provide a switch housing which may be fabricated from a minimum number of component parts, is economical to produce and is highly efficient when used in combination with a movable switch body particularly adapted therefor.

Other objects of this invention will in part be obvious and in part hereinafter pointed out.

The invention accordingly consists in the features of construction, combination of elements and arrangement of parts, which will be exemplified in the structures hereinafter described, and of which the scope of invention will be indicated in the claims following.

In the accompanying drawings:

Fig. 1 is a vertical section of a switch body embodying the invention; Fig. 2 is a side elevational view thereof;

Fig. 3 is a vertical section of a switch body embodying the invention and illustrating a modification thereof; Figs. 4 and 5 are side elevational views, showing different rotated positions thereof;

Fig. 6 is a vertical section of another modified form of switch body; Fig. 7 is a side elevational view thereof;

Fig. 8 is a side elevational view of a switch hous-

2

ing embodying the invention and a switch body mounted therein; Fig. 9 is a transverse sectional view thereof;

Fig. 10 is a side elevational view of a contact member of the switch housing shown in Fig. 8;

Fig. 11 is a vertical section of a switch body showing modified form of terminals; Fig. 12 is a side elevational view thereof; Fig. 13 is a top plan view of a contact member for use with the switch body shown in Fig. 11;

Fig. 14 is a vertical section of still a further modified form of switch body;

Fig. 15 is a side elevational view of a switch body showing means for rotating the same; and

Fig. 16 is a side elevational view of the switch body shown in Fig. 7 and rotated to its "off" position.

Referring in detail to the drawing and particularly to Figs. 1 and 2, 10 designates a switch body embodying the invention. The same comprises a pair of similar, juxtaposed walled members 11 which are secured together to form a hermetically sealed chamber 12 between the members.

Each of the members 11 comprises a dished circular wall 13 from which there extends outwardly a peripheral portion 14. The members 11 are formed of a molded vitreous material such as glass. The members 11 are readily bonded together by fusion of the opposed faces of the peripheral portions 14.

The members 11 are provided with aligned terminal pins 15 hermetically sealed into walls 13 and disposed transversely thereof. The inner end of pins 15 extend to the chamber 12 while the outer ends of the pins project exteriorly of the walls 13. As shown in Figs. 1 and 2, the pins 15 are eccentrically related to the axis of the circular walls 13. One of the pins 15 may be hollow to permit the exhaustion of the chamber 12, following the introduction of a small amount of mercury 17 into the chamber. The exhausted air is replaced by gas such as helium, nitrogen, carbon dioxide, or the like. The hollow pin is then suitably sealed.

A radially extending handle 18 may be fixed to the body 10 by having its inner end suitably secured to a selected portion thereof. The handle may be of metal and fused to the vitreous members or it may be of a non-metallic material, such as plastic or the like, in which case it may be cemented or otherwise secured to the vitreous members.

The switch body 10 may be mounted in a suitable housing provided with opposed contacts 55 adapted to be interconnected in an electrical cir-

cuit and which may be engaged by the terminals 15 while said body is rotated through a predetermined angle by means of handle 18 which is adapted to project exteriorly of the housing. It is understood that in one position of the body, the pins 15 are immersed in the pool of mercury 17, thereby electrically interconnecting the same to complete the circuit, while in another position of the body, the pins 15 will be disposed above the level of the mercury pool 17, as shown in Fig. 2, thereby electrically disconnecting the terminals and breaking the circuit.

To reduce arcing effects within chamber 12, the pins 15 may be in offset relation to each other, whereby, on rotation of the body 10, only one of the pins 15 emerges from the mercury pool 17, to break the circuit.

In Figs. 3, 4 and 5 is shown a switch body 20 illustrating a modification of the invention. The same comprises a pair of similar, juxtaposed circular vitreous members 21. Each of these members includes a wall 22 formed with a recess 23 on one face thereof, disposed eccentrically of the transverse axis of the wall. The members 21 further include oppositely disposed face portions 24. The members 21 are readily fused together at the opposed faces of the portions 24. The opposed recesses 23 will thus form a hermetically sealed chamber 25. Metal alloy pins 26 are hermetically sealed into the walls 22 transversely thereof to provide terminals. The terminals are disposed at the transverse axis of rotation of the body 20 and extend to the lower portion of chamber 25 as shown in Figs. 3, 4.

The chamber 25 has a small amount of mercury 27 introduced therein through one of the pins 26 in the manner previously described. On rotating the body 20 about its terminals 26 as an axis, by means of a handle 28 extending from the body, from the position shown in Fig. 4 to the position shown in Fig. 5, the terminals will maintain their axial position while the mercury level will change from a position covering the inner ends of the terminals to a position uncovering the terminals, thereby electrically disconnecting the same.

In Figs. 6 and 7 is shown a switch body 30 similar to that shown in Figs. 1, 2, except as hereinafter described. The dished members 11 enclose a ceramic barrier disc 31. The disc 31 is of a thickness substantially equal to that of chamber 12 between the members 11 and is formed on its opposite faces with recesses 32 which are interconnected by a transverse opening 33. The terminals 15 in walls 13 are disposed slightly out of alignment with opening 33. In one position of the body 30, the mercury 17 extends on either side of the disc 31 as well as in the opening 33 therein so as to electrically interconnect the terminals 15. On rotating the body 30 through a predetermined angle by means of handle 18, the opening 33 in disc 31 will be above the level of the mercury 17, as shown in Fig. 16, thereby dividing the mercury pool into two separated portions and breaking the circuit between the terminals.

The switch bodies 10 and 30 may be mounted for rotation in a switch housing 40 which comprises a pair of walled members 41 in opposed relation, as shown in Figs. 8, 9. The members 41 may be formed with suitable recesses 42 to receive the switch body. The members 41 are further formed on their inner surfaces with arcuate grooves 43. Disposed within the grooves 43

are arcuate strips 44 of contact metal formed with arcuate grooves 45 for receiving the terminal pins 15 and guiding the same during their arcuate movement upon rotation of the switch body. Extensions 46 of the strips 44 project outwardly of the housing and are provided with screws 47 to form terminal connectors. The handle 18 on the switch body projects through an opening 48 in the housing to permit rotation of the switch body through a predetermined angle. The rotation of the switch body makes or breaks the circuit in which the switch is connected, in the manner previously described.

The angular extent of the arcuate grooves 45 in contacts 44 will determine the limits of rotation of the switch body and form stops to establish "on" and "off" positions of the switch.

In Figs. 11, 12 and 13 are shown a further embodiment of the invention. The same comprises a switch body 50 which includes dished vitreous members 11 and a sealed mercury chamber 12, as previously described. Each of the members 11 has secured to the outer face thereof, a terminal 51. The terminal 51 includes a portion 52 extending through the walls of member 11 and projecting into chamber 12. Each of the terminals 51 is further formed with a pair of curved, concentric flanges 53 connected at their opposite ends to form an arcuate guideway 54.

The switch body 50 may be mounted for rotational movement in a switch housing similar to housing 40 except as hereinafter described. The housing walls are formed to receive contact members 61. As shown in Fig. 13, members 61 include pins 62 at right angles thereto, such pins being receivable in guideway 54 of terminals 51 and making sliding contact therewith upon rotation of the switch body 50. The contact members 61 may be of spring metal, suitably biased toward each other to resiliently press the pins 62 against members 51 of the switch body 50. The members 61 also include terminal screws 63 for making suitable connections with the wiring with which the switch is associated.

In Fig. 14 is shown a switch body 70 which includes a pair of dished vitreous members 71 which are fused together to form a hermetically sealed chamber 72. Interposed between the members 71 is an annular metallic member 73 of T shaped transverse section. The member 73 becomes sealed between the fused members 71 and provides an outer rim portion 74. The rim portion 74 may be used to secure a handle thereto for rotating the switch body. Also, the rim portion 55 may provide a bearing surface for the switch body relative to the housing in which the switch body is mounted.

The dished vitreous bodies used in making the liquid contact switches, referred to hereinabove, may be of glass or glassy material of a suitable fusing point. The terminals fused into the dished members are made of suitable metals or metal alloys well known in the art and selected in terms of the particular glass used in making the vitreous members, to insure the proper hermetic seal therebetween.

The switch bodies may be provided with one or more notches on peripheral portions thereof, to attach handles having portions removably engaged in said notches. Since the bodies are of insulating vitreous material, the notch engaging portions of the handle may be of spring metal suitably flanged to engage the notches. Such an arrangement is shown in Fig. 15 wherein the peripheral portion of switch body 10 is formed with

notches 80. A handle 18a includes a spring metal portion 81 with flanges 82 at opposite ends thereof which may be snapped into notches 80.

It will thus be seen that there is provided electric switches in which the several objects of this invention are achieved and which are well adapted to meet the conditions of practical use.

As various possible embodiments might be made of the above invention, and as various changes might be made in the embodiments set forth, it is understood that all matter herein set forth or shown in the accompanying drawings is to be interpreted as illustrative and not in a limiting sense.

Having thus described my invention, I claim 15 as new and desire to protect by Letters Patent:

1. A switch comprising a housing including a pair of opposed walls, opposed facing contact means on said walls, a rotatable circuit closer located between said contact means and including terminals respectively associated with each of said contact means, each pair of associated contact means and terminals having relative slidable engagement in a predetermined arcuate path.

2. A switch as in claim 1, wherein said terminals are eccentrically disposed relative to the transverse axis of said circuit closer and said contact means comprises arcuate strips.

3. A switch as in claim 1, wherein said contact means are eccentrically disposed relative to the transverse axis of said housing and said terminals comprise arcuate strips.

4. A switch comprising a housing including a pair of opposed walls, arcuate contact strips on said walls in opposed facing relation to each other, a rotatable liquid contact closer between said

strips, said closer having outwardly projecting terminals eccentrically related to the axis of rotation of said closer, each of said terminals slidably engaging one of said contact strips respectively, and means for rotating said closer.

5. A switch as in claim 4, wherein said contact strips include means for limiting the extent of rotation of said closer.

6. A switch comprising a housing and a rotatable circuit closer mounted therein, said closer including a pair of terminal members eccentrically located relative to the rotational axis thereof and movable in an arcuate path upon rotation of said closer and contact members on said housing respectively engageable with said terminal members throughout the movement thereof.

7. A switch comprising a housing including opposed walls, a pair of contacts mounted on said walls respectively, each of said contacts including 20 a curved strip having a depressed portion of arcuate extent, a circuit closer rotatably mounted between said contacts and including a pair of projecting terminals eccentrically located relative to the rotational axis thereof and respectively received in the depressed portions of said contacts, 25 said closer being rotatable about a transverse axis while said terminals slidably engage said contacts.

MANNES N. GLICKMAN.
